UNITED STATES PATENT OFFICE.

SELDEN T. PORTER, OF NORWICH, CONNECTICUT.

STEAM-BOILER.

SPECIFICATION forming part of Letters Patent No. 309,092, dated December 9, 1884.

Application filed July 5, 1884. (No model.)

To all whom it may concern:

Be it known that I, SELDEN T. PORTER, of the city of Norwich, county of New London, and State of Connecticut, have invented certain new and useful Improvements in Steam-Boilers, which improvements are fully set forth and described in the following specification, reference being had to the drawings which form a part of and accompany this specification.

My invention relates to certain improvements in the so-called "sectional steam-boilers," used principally for heating purposes, my immediate object being to simplify and strengthen somewhat certain parts of such boilers, and also to provide a form of boiler in which the water shall be so divided and distributed around and over the fire-pot that steam may be quickly generated, and when once generated held at a desired temperature with a small body of fire. It is also my purpose to bring the fire and the water to be heated and converted into steam as closely together as possible.

25 Inasmuch as some of the elements of my invention are improvements on Patent No. 207,771, granted to Wm. H. Page, September 3, 1878, I have not described in detail the construction of such elements, but will refer 30 to said patent for the description of certain parts hereinafter specified.

Briefly stated, my invention consists, first, of an improved method of securing to the "base-rim" and "crown-sheet" the ends of the several staves or sections which form the fire-pot; second, of making said sections as a true arc of the circle which they are to form when joined together; third, of securing to the crown-sheet an urn-shaped section, C, 40 hanging immediately over the fire-pot, and provided with a series of radial water-chambers, with a view to dividing the water-space; fourth, a funnel-shaped compartment, D, whose lower end is secured to an upward extension on the urn C, before referred to, said funnel-shaped piece D being located within the boiler proper, and forming with suitable connecting-flues an exit or draft for the hot air; fifth, an elongated water-vessel, E, hung 45 at its upper end in the funnel-shaped case D, and whose lower end reaches below the urn C, my object in thus extending said water-vessel

below said urn being to bring a portion of the water as near as possible to the hottest part of the fire—that is, to the center of said fire. 55

In the accompanying drawings, Figure 1 is a front elevation of my steam-heater as it appears when cased up ready for use. Fig. 2 is a vertical section on line *x x* of Fig. 1, the grate being removed. Fig. 3 is a top detached 60 view, somewhat enlarged, of the central water-vessel, E. Fig. 4 is a top sectional view of the boiler proper, taken on line *z z*, Fig. 2, showing the flues *a a*, which lead outward from the funnel D. Said Fig. 4 also shows a 65 top view of said funnel and of the central water-vessel, E. Fig. 5 is a detached top view of my base-rim B. Fig. 6 is a top view of one of the hollow sections *b*, which form the barrel or fire-pot of my heater. Fig. 7 is a detached view, top and side, of the urn C. Fig. 8 shows top and side views of the funnel D. 70

The barrel or fire-pot of my heater is formed of a series of hollow staves or sections, *b*, preferably six in number, the lower ends of said sections resting on ledges *c c* and cross-ties *d* in the grooved base-rim B. This method of supporting and securing the sections *b* in the base-rim is one of my improvements on the method adopted in the patent to Page above 8c referred to. The fire-pot in said patent to Page is formed of a series of sections whose exterior, when joined together, presents a scalloped or foliated outline, the lower end of said sections being held in the rabbeted base- 85 rim on a line or level with said base-rim.

I find in practice as the several sections are being securely cemented in place there is a constant liability (as the cement is tamped home) to crowd the slight rim or rib on the 90 outer side of the sections outward, and thus to crack the base-rim, and to overcome this serious objection I have constructed my base-rim with a circular groove having strengthening-ledges and cross-ties located a considerable distance below the plane of the base-rim proper. By thus supporting the sections *b* below the plane of the base-rim I obtain the full strength of the broad flange or plate *e* when tamping in the cement, instead of depending on a slight rib, as in the Page patent, and the ledges and cross-ties also provide a solid foundation or support for the sections *b* to rest on. In practice I swell the ends of the 95 100

sections *b* so that when cemented in place they are practically dovetailed into the base-rim and crown-sheet.

On the upper end of the barrel formed by the series of sections *b* is located a crown-sheet, *F*, formed with a series of radiating hollow arms, in principle substantially like that shown and described by said Page. The top central opening of the crown-sheet *F* is provided with an internal screw-thread to receive and support the threaded neck on the underside of the boiler proper, which is shown at *H*, and is also substantially as in the patent to Page. The lower central opening in the crown-sheet *F* is threaded to receive the urn-shaped casting *C*. Within the outer shell of said casting *C* is a second cylindrical shell or neck, *i*, (see Fig. 7,) extending somewhat above the outer shell, and threaded to receive the funnel-shaped piece *D*, whose top central hole is in turn threaded to receive the hanging water-vessel *E*. The casting *C* has its lower portion formed with a series of radiating hollow arms, *h*, which are suspended below the crown-sheet and immediately above the fire-pot, presenting a large amount of heating-surface to the fire, yet allowing the fire to pass freely upward to and between the arms of the crown-sheet.

It is a well-known fact that a given amount of heating-surface immediately over or within the fire-pot (as in the case of the arms *h*) is more economically heated than the same amount of heating-surface around or outside of said fire-pot. The water-vessel *E* is provided at its upper end with one or more apertures, *k*, which open into the boiler *H*.

It will be evident that the section *C* could be formed with a closed top, and the pieces *D* dispensed with; or, if so desired, the water-vessel *E* could be added by so forming its upper end that it could be screwed onto the neck *i* in place of the funnel *D*. It will also be seen that the sections *D C* could be dispensed with and the water-vessel *E* screwed into the lower opening in the crown-sheet in place of the piece *C*, as now shown in the drawings. Such combinations would necessitate certain changes in the size of the parts mentioned, but would not alter their general shape nor impair their utility.

The space between the water-vessel *E* and the inner walls of the funnel-shaped case *D* is connected with and exposed to the fire by the central opening in the piece *C*, and to cause a continuous circulation of hot air in said space

I provide one or more pipes or flues, *a a*, which, as before stated, lead outward through the shell of the boiler *H*. By thus "cutting up" the water-space in my heater I am able to present the water to the fire in thin sheets or small bodies, which "feel" the effect of the fire much quicker than would a large tank of water.

Having thus described my invention, I claim as new and wish to secure by Letters Patent—

1. In combination with a fire-pot composed of a series of vertical staves or sections, a crown-sheet supported on and secured fixedly to said fire-pot, a boiler, *H*, secured detachably to the upper shell of said crown-sheet, and an urn-shaped section, *C*, secured detachably to the lower shell of the crown-sheet, said section *C* being provided with a series of radial water-chambers, *h*, located below the crown-sheet and within the fire-space, substantially as and for the purpose specified.

2. In combination with a cylindrical sectional fire-pot, a crown-sheet, *F*, supported on said fire-pot, a boiler, *H*, secured to the upper shell of the crown-sheet, an urn-shaped section (having the radial water-chambers *h*) attached to the lower shell of the crown-sheet, and the funnel-shaped section *D*, secured to the inner neck, *i*, of section *C*, tubes or flues *a a*, leading outward through the boiler *H*, being provided to form a draft-connection between said section *D* and the draft proper, as and for the purpose specified.

3. In combination with a cylindrical sectional fire-pot, a crown-sheet, *F*, supported on said fire-pot, the boiler *H*, secured to the upper shell of the crown-sheet, the urn-shaped section *C*, (having radial water-chambers *h*), secured to the lower shell of the crown-sheet, the funnel-shaped section *D*, secured to the inner neck of section *C*, and the water-vessel *E*, said water-vessel being secured in the upper plate of section *D*, and provided with apertures *k* opening into the boiler proper, substantially as and for the purpose specified.

4. A fire-pot composed of a series of hollow vertical sections, in combination with a base-rim grooved to receive said sections, and provided at a considerable distance below the level of the flange *c* with strengthening-ledges *c c* and cross-ties *d*, on which the sectional fire-pot rests when in place, as and for the purpose specified.

SELDEN T. PORTER.
